[57] ABSTRACT

A device for supporting a flag staff. This device includes a sleeve with a stabilizing plate attached thereto which will enable it to remain permanently in the ground, the sleeve portion receiving the flag staff which is removable therefrom.

1 Claim, 3 Drawing Figures

PATENTED OCT 24 1972

FLAG STAFF ANCHOR

This invention relates to flags, and more particularly to a flag staff anchor.

It is therefore the primary purpose of this invention to provide a flag staff anchor which will enable the user to display a flag on the lawn rather than from the side of the building.

Another object of this invention is to provide a device of the type described which will have a hollow sleeve portion with a stabilizer plate welded thereto, the combination forming a permanent support within the ground.

A further object of this invention is to provide a flag staff anchor which will receive the lower extremity of the flag staff freely so that the flag staff may be removed if desired.

Other objects of the present invention are to provide a flag staff anchor that is simple in design, inexpensive to manufacture, rugged in construction, easy to use and efficient in operation.

These and other objects will be readily evident upon a study of the following specification and the accompanying drawing wherein:

FIG. 1 is a vertical view of the present invention shown in elevation and partly broken away;

FIG. 2 is a cross-sectional view taken along the lines 2—2 of FIG. 1; and

FIG. 3 is a vertical view of the present invention shown installed in the ground and with a flag staff projecting therefrom.

According to this invention, a flag staff anchor 10 is shown to include a hollow elongated sleeve 11 having a stabilizer plate 12 which is welded to a U-shaped member 13.

The extending portions of U-shaped member 13 are welded to the outer periphery of sleeve 11. The stabilizer plate 12 is provided with a point 12' at its lower extremity and is provided with points 12'' at its upper extremity.

The points 12'' of stabilizer plate 12 serve to restrict a lateral and upward movement when device 10 is placed within the ground 14.

Flag staff anchor 10 is of such structure so as to remain stationary within the ground 14 and will receive the lower extremity of the flag staff 15 in a removable manner in order that flag staff 15 may be removed when desired.

It shall be noted that the stabilizer plate 12 serves to restrict the sleeve 11 from moving within the ground when force is applied to the staff 15 accidentally.

The combination of the sleeve 11 portion and the U-shaped member 13 plus the stabilizer 12 serves to restrict any motion of flag staff anchor 10 in a 360° radius when it is placed within the ground 14.

What I claim is:

1. A flag staff anchor for removably receiving a flag staff, comprising a U-shaped member adapted to be driven into the ground, a hollow sleeve welded to the legs of the U-shaped member, said hollow sleeve being adaptable for freely receiving a flag staff, stabilizer plate welded to the apex of the U-shaped member, said stabilizer plate being pointed at a lower end and V-shaped at an upper end, said pointed lower end serving to enable the stabilizer plate to be entered easily into the soil and said V-shaped portion serving to restrict upward or lateral motion, said stabilizer plate extending beyond the periphery of the U-shaped member to restrict rotation of the flag staff anchor.
